UNITED STATES PATENT OFFICE.

GOTTFRIED STUPAR, OF CHICAGO, ILLINOIS.

ELECTRIC PERMUTATION-LOCK SWITCH.

1,098,852.

Specification of Letters Patent.

Patented June 2, 1914.

Application filed December 6, 1912. Serial No. 735,190.

To all whom it may concern:

Be it known that I, GOTTFRIED STUPAR, a citizen of the United States, residing at Chicago, in the county of Cook and State of Illinois, have invented certain new and useful Improvements in Electric Permutation-Lock Switches, of which the following is a specification.

My invention relates to improvements in electric permutation lock switches.

One of the objects of my invention is to provide an electric switch that can be operated only after certain instrumentalities have been moved in predetermined order as in a combination lock.

Another object of my invention is to provide a means whereby an alarm, such as the ringing of a bell, the lighting of a lamp, or both, or any other alarm signal, may be established or instigated in the event that a false step be made in the operation which is a condition precedent to the moving of the switch members to close an objective electric circuit.

Other and further objects of my invention will become readily apparent to persons skilled in the art from a consideration of the following description when taken in conjunction with the drawings, wherein—

Figure 1 is a plan view of the device; Fig. 2 is a central vertical section of the same; Fig. 3 is a longitudinal section taken on line 3—3 of Fig. 2; Fig. 4 is a transverse section taken on line 4—4 of Fig. 3; Fig. 5 is a section taken on line 5—5 of Fig. 2; and Fig. 6 is a diagram of the circuits.

In all the views the same reference characters indicate similar parts.

10 is a casing of suitable material for containing the operative mechanism of my switch. It is provided with a base 11 and a top 12 that may be secured thereto by any suitable means.

The rod 13 passes through the casing and is provided on its upper end with a rotatable knob 14 fixed thereto and carrying a disk 15 provided with a pointer 16. These parts are secured to the rod 13 by means of a pin 17. A guide sleeve 18 is insulatedly secured to the top 12 by means of the screws 19. The sleeve 18 carries near its lower end an annular shoulder 20, against which bears the rotatable disk 21. The disks are sup-

ported in position on the sleeve by means of a washer 23, which prevents them from falling off of the sleeve and permits free rotation thereof so that the disks 21 and 22 may be freely rotated on the sleeve 18 when supported by the washer 23.

A sleeve 24 is vertically movable on the rod 13, such movement being limited by means of the slot 25 and the pin 26. The sleeve 24 is provided with a flange 27 upon which is carried a toothed wheel 28, having a series of teeth 29. The sleeve 24 is secured to the wheel by means of insulated screws 30. When the knob 14 is rotated, the wheel 29 may be rotated through the instrumentality of the rod 13 and the pin 26 in the slot 25. A pin 31 is secured in the lower disk 22 and is adapted for engagement between any two of the teeth 29 of the wheel 28, so as to establish a relation between the disk 15 (rotatable with the shaft 13) and a given point of the disk 22.

Nuts 32 are threaded on the lower end of the rod 13 and, through the instrumentality of an insulating washer 33, they support the sleeve 24 and the notched wheel 28, with pin 31, in normal engagement between two adjacent teeth 29 of the said wheel. The nuts are tightened so as to produce sufficient friction between the disks 21 and 22 to cause the former to be rotated when the latter is rotated by means of the knob 14, there being no material resistance to prevent rotation of the disk 21. Only a small amount of friction is necessary to effect its rotation by means of the disk 22. The upper disk 21 is provided with a vertically extending pin 34.

It is also provided with a notch 35, made in its periphery, having a definite fixed relation with the pin 34. A stop for the pin 34 is provided by a bracket 36, which is secured to the side wall of the casing and has an insulating plate 37 against which the pin 34 impinges. When the pin 34 is against the stop 36, the slot 35 is in position shown in Fig. 3.

A depressible rod 38 carries a knob 39, and is provided in its upper surfaces with annular grooves 40 and 41 in which a spring-pressed bolt 42 engages to hold the rod 38 in the position in which it has been placed. A vertical longitudinal slot 43 is made in one side of the rod into which pro-

jects a fixed bolt 44 which prevents rotation of the rod 38. The rod 38 is reduced, as at 45, and over this reduced part is secured an insulated sleeve 46. The sleeve is made 5 larger, as at 47, and at this point carries a laterally projecting stud 48, upon which is mounted a cross-shaped circuit-closing member 49. This member is provided with four radially disposed metallic arms 50, 51, 52, 10 and 53, that are electrically connected together and are in electrical contact with the insulated sleeve 46. The cross-shaped part 49 is curved and is preferably made of hard rubber, or other similar insulating material. 15 A brush 54 makes resilient contact with the sleeve 46 and is connected with the binding screw 55 so as carry the electric current to the arms 50 to 53 inclusive. When this cross-shaped structure, just described, is rotated in clock-wise direction, a spring detent 56 engages the arms 50 and 53 inclusive, in turn, and prevents the rotation of the structure in the opposite direction.

A vertically extending bracket 57 forms a 25 coöperating circuit-closing member with the arms 50 to 53 inclusive, or any one thereof, and is connected with the binding screw 58 which is secured in the bottom wall 11 of the casing, so that when any one of the arms 50 30 to 53 inclusive is brought into contact with the part 57 a circuit will thereby be closed.

The upper disk 21 bears a series of upwardly projecting teeth 59, the function and operation of which will be hereinafter described. The disk 22 is provided with a slot 60, similar in purpose and object to the slot 35 in the disk 21.

With the position of the parts as shown in Fig. 2, if the stem 38 be depressed by a 40 pressure applied to the knob 39, the metallic arm 53 will pass through the slots 35 and 60 of the disks without making contact with either of the disks 21 or 22 and without being obstructed by them, and when the arm 45 53, or other such arm, makes contact with the switch member 57, the spring bolt 42 will have been brought into notch 40 of the stem 38 and the contact so made will be held intact by this means, so that the circuit will 50 be completed and maintained between the binding screws 55 and 58 through the parts heretofore described. These binding screws 55 and 58 may be connected in an electric circuit with a proper source of electric current and with any device desired to be operated, when the stem 38 is depressed in the manner described.

The binding screw 61 is connected to the sleeve 18 by means of the wire 62.

Now referring to Fig. 6, the diagram of circuits, it will be observed that, should the stem 38 carrying the tube 46 be depressed until the part 53 makes contact with the upper disk 21, as when the slots 35 and 60 of

the respective disks are not in a coincident 65 plane with the path taken by the arm 53 when the stem is depressed, and circuit be thus completed between the disk 21 by virtue 70 of contact of the arm 53 therewith, then circuit will be closed and completed from the battery B over the wire 63 to the alarm bell 64 and over the wire 65 to the terminal 61, through the disk 21 to the contact arm 53, and thence to the terminal 55, and over the wire 66 to the opposite terminal of battery B, thus ringing the alarm bell 64 or lighting a lamp which may be placed in circuit in lieu thereof, or instigating any other convenient signaling means, at a remote point, as may be desired, and thereby indicating that there is some unauthorized person tampering with the switch lock. The signal 64 may be established in the manner described, without the knowledge of the person who is attempting to operate the lock. 85

After the rod 38 has been depressed in the manner described, and contact has been established between any one of the arms, as the arm 53, and the member 57, without establishing the alarm circuit to which reference has been made, any suitable device may be energized in the objective circuit for any particular use or object. If it be desirable, however, that any one of a plurality of circuits be energized, any one of which may be 90 established after the contact has been made between the arm 53 and the member 57, I provide a supplementary switch which may be located inside of the casing 10, as shown, or it may be located at some point remote 95 from the casing, as desired. The switch consists of the rod 67, provided with a turn knob 68 having an index pointer 69. To the lower end of the rod 67 is connected a switch arm 70 which is adapted to make contact with 100 the stationary switch member 71 and any one of the coacting stationary members 72, 73, or 74, as desired, upon turning of the knob 68. Coöperating indications 72', 73', and 74' are made upon the upper surface of 105 the casing so that, in conjunction with the pointer 69, the switch lever or arm 70 may be moved so as to close any one of the circuits communicating with the contacts 72, 73, or 74. Thus, when the switch arm 70 110 makes electrical connection with the contact 72, the circuit is closed through an electro-responsive device 75, which may be employed for any useful purpose desired; when electrical connection is made with contact 115 73, the circuit will be closed through the electric lamps 76; and likewise, when the arm 70 makes electrical connection with the contact 74, the circuit will be closed through 120 an electric lock 77 or the like. Thus any one 125 of the circuits may be energized and may remain energized so long as connection is established and maintained between any of

the arms, as the arm 53, and the member 57. After the rod 38 has been depressed to establish this connection, the disks 21 and 22 may be rotated so that the slots 35 and 60 are no longer in the path of the reciprocating cross 49 in order that the combination will not be shown on the top of the casing for the information of any unauthorized person. Therefore, when it is desired to break connection between the arm 53 and the member 57, the rod 38 is lifted bodily and the insulating portion 49 of the cross, coming in contact with the under surface of the disk 22, will cause the cross part to rotate, at which time the arm 52 of the cross member will be brought into position now occupied by the arm 53 and the spring clip 56 will snap against the trailing side of the member 50 and prevent the cross from being operated in the opposite direction. Thus, at each reciprocation of the rod 38, the cross will turn one-fourth of a revolution, provided that slots 35 and 60 are not in the path of the cross, as heretofore described.

For operating the combination, so as to bring the slots 35 and 60 in proper relation with the cross, in order that the cross may be depressed and one of its members make electrical connection with the member 57, the knob 14 is rotated to the left until the pin 34 on disk 21 makes contact with the stop 36, and at this time the notch or slot 35 will be brought into position shown in Fig. 3. Now when the knob is further turned to the left, or in the same direction, the stop 36 will prevent the disk 21 from turning with the disk 22, by its frictional engagement therewith, but inasmuch as there is a positive connection between the disk 22 and the stem 13, by means of the slot 25 and the pin 26 and the disk 28 and the pin 31, further rotation of the stem 13 will cause the disk 22 to be rotated to any desired position. There is an established relation between the slot or notch 60 of disk 22 and the index 78 on the top of the casing, so that when the pointer 16 is brought to a predetermined position on the index, by rotating the knob 14, it will be known thereby that the notch 60 is in proper alining position with the reciprocable cross 49 and that the rod 38 may be safely depressed for making contact between a selected arm of the cross and the member 57 without danger of ringing the alarm bell.

The relation between the dial 15 and the slot 60 of disk 22 may be varied or changed and thus the combination may be changed, by removing the nuts 32 from the rod 13, permitting the sleeve 24 and the disk 28 to fall a distance limited by the slot 25 and the pin 26, until the pin 31 of disk 22 is clear of the notches 29 in the wheel 28 when the sleeve 24 and the dial 15 may be rotated to

another position with reference to disk 22 65 while the disk 22 remains stationary, thus changing the relation between the dial 15 and the notch in disk 22 to suit any conditions that may be desired. After this operation the sleeve 24 is raised until the pin 70 31 engages another notch in the disk 28 when the nuts 32 may be tightened in place on the rod 13.

I have shown a number of teeth 59 on the upper surface of the disk 21. The object 75 of these teeth is to prevent a person from depressing the rod 38 and rotating the knob 14 for the purpose of finding the slot 35 in the event that the alarm circuit should be broken. When the rod 38 is depressed, so 80 that any one of the conducting arms 50 to 53 inclusive makes contact with the surface of the disk, the teeth 59 will prevent rotation of the disk. This is a precaution, however, that is not necessary when the alarm 85 circuit is in order.

While I have herein described a single embodiment of my invention, for the purpose of clear disclosure, it is evident that changes 90 may be made within the scope of the appended claims and without departing from the spirit of my invention.

What I claim is:

1. In a device of the character described, a casing; a plurality of commutable disks, 95 each having a peripheral slot which, when registering with the other slots provides a vertical open passage through the rim of the disks; a movable switch element adjacent the disks, a fan-shaped wheel of insulating 100 material secured to the movable switch element and rotatable about an axis at right angles thereto; contact elements, secured to each of the said blades, and electrically connected together, and a stationary switch element, on the opposite side of the disks, and adapted to make contact with any one of the elements on the rotatable wheel, the said wheel being so positioned as to permit the passage of one of the blades through the 110 slots in the disks when they are properly registered and permit the upward passage of the movable switch element by rotation of the wheel when the disks are in a position when the slots do not register. 115

2. In a device of the character described, the combination of a plurality of commutable disks, each having a peripheral slot which, when registering with the other slots provides a vertical open passage through the 120 rim of the disks; a movable switch element adjacent the disks, a fan-shaped wheel secured to the movable switch element and rotatable about an axis at right angles thereto; and a stationary switch element, on the 125 opposite side of the disks, and adapted to make contact with any one of the arms of the fan-shaped wheel the said wheel being

so positioned as to permit the passage of one of the blades through the slots in the disks when they are properly registered and permit the upward passage of the movable switch element by rotation of the wheel when the disks are in a position when the slots do not register.

In testimony whereof I hereunto set my hand in the presence of two witnesses.

GOTTFRIED STUPAR.

In presence of—

**W. LINN ALLEN,
MARY F. ALLEN.**
